UNITED STATES PATENT OFFICE.

JOSEPH J. SCOTT, OF CLINTONVILLE, PENNSYLVANIA, ASSIGNOR OF ONE-HALF TO
FRANK GREEN, OF CLINTONVILLE, PENNSYLVANIA.

WALL-PACKER FOR WELLS.

1,034,737.

Specification of Letters Patent. Patented Aug. 6, 1912.

Application filed November 20, 1911. Serial No. 661,201.

To all whom it may concern:

Be it known that I, JOSEPH J. SCOTT, citizen of the United States, residing at Clintonville, in the county of Venango and 5 State of Pennsylvania, have invented certain new and useful Improvements in Wall-Packers for Wells, of which the following is a specification.

The object, construction and application 10 of my invention are herein set forth with sufficient clearness to enable those skilled in the art to which it appertains to make and use the same.

The object of my invention is, to supply 15 an efficient packer to be attached to the tubing of an oil well, whereby the casing in which said tubing is located may be packed, so that no water can flow downward in the same, past the packer into the oil or oil- 20 producing stratum of the well.

One form of construction of my improved packer is clearly illustrated in the accompanying drawings, but inasmuch as said construction could be modified in certain 25 particulars, without departing from the scope of my invention, said drawings are to be considered as illustrative of merely one method of mechanically embodying or expressing my inventive idea.

30 The respective figures of said drawings are as follows:—

Figure 1 is a central, longitudinal section through my packer, showing the same in the normal condition. Fig. 2 is an elevation of 35 my improved packer showing the same in the expanded condition. Fig. 3 is a bottom view of the packer. Fig. 4 is a bottom view of the packer in position in the casing, showing the same in the locked position. In this 40 view the lower element is removed to expose other portions to view. Fig. 5 is a detail.

In detail, the construction here illustrated is as follows:—

I employ a comparatively short section of 45 tubing 1, having a screw-thread 2 at its upper end, adapted for the attachment of an internally screw-threaded head 3. The lower end of said tubing 1 is provided with a comparatively long screw-thread 4, for the 50 reception of an internally screw-threaded compression member 5—(see Fig. 5).—

A flexible, expansive, packing member, consisting preferably of a rubber sleeve 6 is placed between the lower end of head 3 and 55 the upper face of the compression member 5. A metallic sleeve 7 passes through the

packing sleeve 6, which sleeve 7 is longitudinally movable upon the tubing. Between the inner wall of said sleeve 7 and the periphery of the tubing, there is an annular space 8, the object of which will be presently set forth. The upper end of sleeve 7 projects through the packing sleeve 6 and enters an annular chamber 9 in the head 3, in which said sleeve is adapted to have a free longitudinal or vertical movement. Compression member 5 is internally screw-threaded, as shown in Fig. 5, for the reception of the lower screw-threaded end 4 of the tubing nipple 1. The flexible, expansive 60 sleeve 6 is compressed longitudinally and caused to expand laterally or circumferentially, as shown in Fig. 2, by screwing said tubing-nipple 1 downward through said compression member 5.

It is necessary to construct the packer so 65 that sleeve 6 may be expanded after it is lowered into place inside the casing in the well, and in order to be able to do this, I provide means for locking member 5 in the 70 casing so that it cannot revolve, then when the tubing, which extends to the surface of the ground, is turned, nipple 1 is caused to travel downward through the threaded member 5, thus compressing sleeve 6 longitudinally and laterally expanding the same 75 as aforesaid. The tubing which extends from the packer upward to the surface of the ground is indicated at 10. Tubing 10 is also extended downward from the packer.

The means for locking member 5 within the casing is as follows: The lower end of 80 said member 5 is provided with an eccentric extension or hub 11, upon which an eccentric ring 12 is loosely mounted and retained in position by means of a collar 13, which is secured to hub 11 by means of the fillister-head screws 14. Ring 12 is free to turn upon hub 11, and by giving the tubing and the thereto attached packer a quick rotary 85 movement, said ring is caused to turn upon said hub 11 and to assume the position shown in Fig. 4 so that it bears against the inner wall of the casing, thus causing the compression member to interlock with the casing, and when said interlocking has taken place, tubing 1 may be screwed downward 90 through member 5, thus expanding sleeve 6 so that it completely fills the casing, and prevents water from flowing downward past 95 the packer.

In order to prevent ring 12 from turning

to an eccentric or unaligned position, when tubing 1 is turned in the opposite direction from that mentioned above, a pin 15 is passed through the side of the ring and its inner end enters the slot 15' in hub 11. In the aligned position, as shown in Fig. 2, pin 15 bears against one end of the slot and thus secures the object of its employment. This provision is made for the purpose of preventing ring 12 from assuming the locking position when the tubing is turned in the direction in which it would unscrew, as otherwise it might be accidentally unscrewed and severed when in the well.

15. Provision is made for the passage of gas through the packer in the following manner:—Through the compression member 5 and the collar 13, I form a slot 16 which communicates with the annular space 8 and the chamber 9. In the upper end of head 3 I drill downward as at 16' until chamber 9 is intersected, thus forming a passage entirely through the packer, longitudinally through which gas may pass. A gas escape pipe 17 is then connected with the passage 16' in any suitable manner, which pipe 17 leads and conducts gas to the surface of the ground. An anti-friction ring or washer 18 is interposed between the juxtaposed faces 30 of head 3 and sleeve 6, to allow said head to

turn freely and without friction upon said sleeve.

What I claim and desire to secure by Letters Patent is:

In a wall-packer for wells, the combination with the fluid-conducting tubing of a well, of a flexible packing-member surrounding said tubing, a sleeve attached to said tubing and bearing against the upper end of said flexible member, there being an annular chamber between said tubing and said sleeve, a collar bearing against the lower end of said flexible member, and through which said tubing is inserted, by means of a screw-thread, for the purpose specified, a metallic sleeve resting in said collar and passing through said packing member, with its upper end positioned in the lower portion of said annular chamber, there being an eccentric hub upon said collar, and an eccentric ring loosely mounted upon said hub, adapted to engage the wall of the well, for the purpose set forth.

In testimony whereof I affix my signature in presence of two witnesses.

JOSEPH J. SCOTT.
